UNITED STATES PATENT OFFICE

RALPH O. HELGEBY, OF FLINT, MICHIGAN, ASSIGNOR TO A C SPARK PLUG COMPANY, OF FLINT, MICHIGAN, A COMPANY OF MICHIGAN

JEWEL PLATE FOR SPEEDOMETERS

Application filed May 12, 1928. Serial No. 277,369.

This invention relates to measuring instruments and has been designed more particularly as an improvement in a speedometer for motor vehicles.

5 Among the objects sought to be obtained by the improvements herein described are simplicity in construction and economy in manufacture. The design, because of its simplicity and economy, is particularly 10 adapted for a large scale production. Other objects and advantages will be apparent from a reading of the following specification and an examination of the accompanying drawing.

15 In the drawing:

Figure 1 is a plan view;

Figure 2 is a section on line 2—2 of Figure 1; and

20 Figure 3 illustrates in perspective a detail. Referring by reference characters to the drawing, numeral 10 represents a flat stamping. It is secured to frame 12 by means of screws or other fastening means 14. The frame designated by numeral 12 is that part 25 of the speedometer which is to carry the movable parts of the speedometer and the odometer. It is to be enclosed within a casing, not illustrated. The frame carries a rotor shaft 3 provided with a gear element 30 1 for driving the odometer mechanism.

The speedometer indicating member is designated by numeral 5. It is preferably, as shown in the drawing, of cup shape and it surrounds a rotor 7 suitably secured to the 35 rotating rotor shaft 3. The speed indicating cup 5 is carried by a spindle having lower end and side bearings within the upper end of the rotor shaft, as is commonly done and as is illustrated in Figure 2.

40 The flat stamping 10 may be reinforced by a rib 16, as shown in Figure 1. Integral with stamping 10 is an arm 18 which is bent down from the plane of the stamping, as best shown in Figure 2. This arm is to 45 serve as a stop and is engaged by part 20 carried by the rotating indicating cup to limit the swinging movement of said indicating cup under the influence of spring 38.

50 The spring 38 is at one end secured to the spindle, as shown in the drawing.

The plate 10 also has an arm 24 lanced out therefrom and bent into U-shape. The upper arm of the U overlies the spindle 26 of the speed indicating cup and serves as a retainer for said spindle. Plate 10 also has a raised part 28 with an opening in the axis of the spindle. Within the depressed part 28 is a hole jewel 30 which is tapered to fit the depressed portion 28. This arrangement for receiving and correctly locating the jewel is quite inexpensive and saves much time in the act of assembling the parts. When assembled, the jewel is staked in position. There is provided a hair spring regulator 32, which is also an inexpensive stamped plate. It is preferably formed with a radially and somewhat upwardly extending arm 32'. It is about the part 28 of plate 10 that an opening in arm 32 fits to permit rotation of said arm. This regulator plate is formed with two lanced out notches 34 and 34' of which one, 34, is bent over the margin of plate 10 and the other, 34', passes through an arc-shaped slot 36 in plate 10 and is also bent over and pinched against the said plate 10. The slot 36 is of sufficient length of arc to provide the necessary swinging of regulator arm 32 to adjust the hair spring. The outer end of arm 32 is cut and shaped, as best shown in Figure 3 at 42, and received between the depressed portions thereof is the end of hair spring 38 and a tapered securing pin 40.

By the provision above described, it will be seen that the one-piece stamping 10 carries integral therewith the speed cup stop 18, the spindle retainer 24 and the hole jewel seat. This reduces the number of parts and thereby saves expense both in material and the cost of assembly. The speed cup stop 18 is easily accessible and may be readily bent for the purpose of adjustment to get an accurate zero reading.

The use of rib 16 sufficiently reinforces the plate 10. The notches 34 and slot 36 afford a very economical and effective arrangement for mounting the hair spring regulator.

Although not shown, it should be mentioned that the magnet for use with such an

instrument is suitably supported on ledges
25 formed on the frame 12.

I claim:

5 In a measuring instrument having as parts
thereof an indicating member, a spindle
therefor, yielding means biasing said indicating
member to a zero position, a stamped
plate, a spring regulator rotatably mounted
10 on said plate, said plate having a slot cut on
an arc about the center of rotation of said
spring regulator, said regulator having parts
lanced therefrom and bent over adjacent por-
tions of said frame, one of said parts being
passed through said slot.

15 In testimony whereof I affix my signature.
RALPH O. HELGEBY.
